UNITED STATES PATENT OFFICE.

WARREN HOLDEN, OF PROVIDENCE, RHODE ISLAND, ASSIGNOR TO FOWLER BROTHERS, OF SAME PLACE.

BRACELET.

SPECIFICATION forming part of Letters Patent No. 281,628, dated July 17, 1883.

Application filed April 20, 1883. (No model.)

To all whom it may concern:

Be it known that I, WARREN HOLDEN, of Providence, in the State of Rhode Island, have invented an Improvement in Bracelets, of 5 which the following is a specification.

My invention relates to that class of bracelets in which the two parts of the bracelet are pivoted to each other, so as to move laterally in opening or closing the bracelet; and it consists in the improved construction and arrangement of the parts, whereby a desirable bracelet is produced, as hereinafter fully set forth.

Figure 1 is a side elevation of the bracelet. Fig. 2 is a central section. Fig. 3 is a cross-section taken in the line $\alpha\alpha$ of Fig. 1. Fig. 4 is a side elevation, illustrating the mode of clasping or unclasping the bracelet. Fig. 5 represents an edge view of the bracelet opened.

In the accompanying drawings, A represents the rigid portion of the bracelet, made of sheet-metal stock formed up as shown in the cross-section, Fig. 3, and at one end of the part A is pivoted the curved spring B, which serves to form the opposite portion of the bracelet, and upon which are placed the ornaments or beads, C. The outer end of the spring B is provided with an enlargement, b, forming a shoulder, c, adapted to engage with a catch, d, which is arranged at the outer end of the portion A of the bracelet. The pivot joint is formed of the two pieces of hollow wire, e e, soldered within the groove a; and to the spring B, which forms one half of the bracelet, is soldered the hollow wire sleeve f, thus firmly

pivoting the two parts to each other, so that 35 the free ends of the parts A and B may be moved laterally from each other, as shown in Fig. 5. The beads C are passed loosely upon the spring B, and are secured thereon by soldering the end bead or collar, C', to the spring, 40 and, instead of the beads C, suitable ornaments may be permanently attached to the spring B. In unclasping the bracelet the end of the spring B is to be forced back, as shown in Fig. 4, after which it can be moved laterally 45 to an open position, as shown in Fig. 5.

The spring portion B of the bracelet may be made either round or flat, as preferred, and may be employed either with or without the beads or ornaments.

I claim as my invention—

1. In a bracelet, the combination of the rigid portion A with the spring portion B, pivoted to the portion A for lateral movement, and provided at its outer end with a shoulder, e, 55 adapted for spring engagement with the catch d, substantially as described.

2. In a bracelet, the combination of the rigid portion A with the spring B, pivoted to the portion A for lateral movement, and provided with the ornamental beads C, and shoulder e, 60 adapted for spring engagement with the catch d, substantially as described.

WARREN HOLDEN.
